United States Patent Office

Des. 204,745
Patented May 17, 1966

204,745

RESTAURANT

Samuel Sanfilippo, Oil City, Pa., assignor to The Pizza
Villa, Inc., a corporation of Pennsylvania

Filed May 4, 1965, Ser. No. 85,093

Term of patent 14 years

(Cl. D13—1)

FIG. 1

FIG. 4

FIG. 5

FIG. 1 is a perspective view of the front and left side;
 FIG. 2 is a right elevation as viewed from FIG. 1;
 FIG. 3 is a front elevation;
 FIG. 4 is a rear elevation; and
 FIG. 5 is a section on line 5-5 of FIG. 2.

The dominant features of my design reside in the portions shown in full lines.

I claim:

The ornamental design for a restaurant, substantially as shown and described.
